CLAIM

The ornamental design of a hat, as shown and described.

DESCRIPTION

FIG. 1 is a top, right perspective view of a hat;

FIG. 2 is a top right perspective view thereof;

FIG. 3 is a front view thereof;

FIG. 4 is a left side view thereof;

FIG. 5 is a back view thereof;

FIG. 6 is a right, side view thereof;

FIG. 7 is a top view thereof; and,

FIG. 8 is a top view thereof.

The broken-line outline of the partial human figure assists in illustrating how the claimed design of the hat may appear when worn but forms no part of the claimed design.
